UNITED STATES PATENT OFFICE.

JAMES EDWARD LENHART, OF WARE, MASSACHUSETTS.

DESIGN FOR A PUZZLE-BOX.

SPECIFICATION forming part of Design No. 26,820, dated March 30, 1897.

Application filed February 11, 1897. Serial No. 623,009. Term of patent 34 years.

To all whom it may concern:

Be it known that I, JAMES EDWARD LENHART, a citizen of the United States, residing at Ware, in the county of Hampshire and 5 State of Massachusetts, have invented and produced a new and original Design for Puzzle Boxes or Cases, of which the following is a specification, reference being had to the accompanying drawings, forming part thereof,

10 in which—

Figure 1 is a plan view of my improved puzzle box or case; and Fig. 2, a section on the line 2 2 of Fig. 1, these two views being necessary to fully illustrate my design.

15 The leading feature of my design consists of a rectangular box or case composed of a bottom 5, side walls 6, and end walls 7 and 8, and the said box or case is provided with a plurality of vertical partition walls or flanges 20 which are arranged in the following manner:

20 Arranged centrally of the bottom of the box or case and connecting with the end wall 7 thereof are two short parallel longitudinal walls or flanges 9, each of which connects at 25 its inner end with a diagonal wall or flange 10, which extends outwardly therefrom in the direction of the side walls 6, and each of which is connected at its outer end with a parallel wall or flange 11, which extends backwardly 30 in the direction of the end wall 7, and at the end of each of the walls or flanges 11 is a wall or flange 12, which connects therewith and extends inwardly parallel with the end wall 7, at the inner ends of which are short longitudinal walls or flanges 13, which extend in 35 the direction of the end wall 8 of the box or case and parallel with the walls or flanges 9, and at each side of the walls or flanges 9 and parallel therewith are two short walls or flanges 14. At the opposite end of the box or 40 case and connected with the end wall 8 thereof are two central parallel inwardly-directed walls or flanges 15, which extend inwardly a predetermined distance, and at the 45 inner end of each of which is an outwardly or inwardly directed flange or wall 16, and in the triangular space thus formed are arranged V-shaped walls or flanges 17, and adjacent to the walls or flanges 15, at the outer sides thereof

and parallel therewith, are short walls or flanges 18, which connect at their inner ends with triangular walls or flanges 19, which enclose the triangular wall or flange 16, and adjacent to the walls or flanges 18 and outside thereof are triangular walls or flanges 20, which connect at one end with the walls or flanges 18 and the main branches of which are parallel with the main branches of the triangular walls or flanges 19, and in the space thus formed are closed chambers 21, which are formed by vertical walls or flanges, and between the triangular walls or flanges 20 and the sides of the box or casing on each side are longitudinal walls or flanges 22.

One branch of each of the triangular walls 65 or flanges 19 is parallel with the walls or flanges 10 at the opposite end of the box or casing, and adjacent to said branch of the triangular walls or flanges 19 are walls or flanges 22, which are parallel therewith and which 70 project diagonally in the direction of the longitudinal center of the box or casing and the outer ends of which connect with the side walls 6 thereof, and adjacent to the walls or flanges 10 are other diagonal walls or flanges 75 23, which are parallel therewith and the outer ends of which connect with the side walls of the box or casing, and between the walls or flanges 22 and 23, on each side of the box or casing and parallel therewith, are other diagonal walls or flanges 24, 25, 26, and 27, and the outer ends of the walls or flanges 24, which 80 are adjacent to the walls or flanges 23, are each connected with a longitudinal wall or flange 28, which projects in the direction of 85 the walls or flanges 22, and the outer ends of the walls or flanges 25 and 27 on each side are connected by a longitudinal wall or flange 28, each of which also connects with the adjacent wall or flange 22, and between the inner ends 90 of the walls or flanges 24 is a V-shaped wall or flange 30, and a pin or projection 31 is arranged between the V-shaped walls or flanges 17 and the V-shaped walls or flanges 30.

The entire design is symmetrical in form, 95 and it will be observed that there are symmetrical spaces between all the parallel walls or flanges and that all these spaces are open

either at one or both ends, with the exception of the space 21 adjacent to the end wall 8 of the box or casing.

Having fully described my new and original design, I claim as new and desire to secure by Letters Patent—

The design for a puzzle box or case herein shown and described.

In testimony that I claim the foregoing as my invention I have signed my name, in presence of the subscribing witnesses, this 5th day of February, 1897.

JAMES EDWARD LENHART.
